INSIGNE OR SIMILAR ARTICLE

Mildred S. Orloff, Alexandria, Va., assignor to the United States of America as represented by the Secretary of the Army

Application July 10, 1957, Serial No. 46,879

Term of patent 14 years

(Cl. D29—2)

(Granted under Title 35, U. S. Code (1952), sec. 266)

The invention described herein, if patented, may be manufactured and used by or for the Government for governmental purposes, without the payment to me of any royalty thereon.

It is understood that my design may be embodied in such articles as a medallion, badge, plaque, or sign, without departing from the spirit of my invention.

The essential features of my design are shown in full lines.

I claim:

The ornamental design for an insignia or similar article, as shown and described.
